SLUG CASTING MOLD

Anthony J. Stouges, Queens Village, N. Y., assignor to Mergenthaler Linotype Company, a corporation of New York

Application November 2, 1935, Serial No. 47,949

10 Claims. (Cl. 199—55)

This invention relates to slug casting machines of the general organization represented in U. S. Letters Patent No. 436,532 to O. Mergenthaler, wherein a composed line of matrices is presented 5 momentarily to one face of a slotted mold, and molten metal injected by a pump from a metal pot into the mold slot or cavity to form a type bar or slug against the line of matrices.

In these machines, the mold slot or cavity is 10 usually defined by four distinct parts, namely, a cap portion, a body portion, a left-hand liner and a right-hand liner. These liners are of various thicknesses and are selectively employed to vary the dimensions of the mold slot or cavity 15 according to the size of the slug to be cast, and to save metal in slugs of the larger sizes, such as those of the head-letter or display variety, the cap portion of the mold is provided with a number of spaced core members or sections which 20 terminate short of the body portion and short of the front face of the mold. A slug cast in a mold of this kind, therefore, is of the skeleton form, having a thin body portion, an overhanging face or character bearing portion, and a plurality of supporting ribs which extend from 25 beneath the overhanging face or character bearing portion to the foot of the slug. As usual, the core members are so formed and spaced that when a slug is cast and thereafter cut to a standard length the ribs will provide the overhanging face or character bearing portion of the slug with the support necessary to prevent failure 30 thereof when it is subjected to pressure.

In many instances, however, it is desirable to 35 cut a slug cast in a mold of this sort at an odd length, and when this is done it frequently happens that one end of the overhanging face or character bearing portion extends so far beyond a supporting rib that it fails for lack of 40 support when subjected to pressure.

The present invention is intended to obviate the foregoing objection and contemplates a mold which, while adapted and arranged to cast a skeleton slug, will provide the overhanging face 45 or character bearing portion with additional support and the necessary footage therefor without materially increasing the weight of the slug, and to this end the upper ends of the side faces of the core sections are provided with fore-and-aft 50 grooves in which fins or vanes are cast which extend outwardly along the sides of the supporting ribs from beneath the overhanging face or character bearing portion to the foot of the slug.

These fins or vanes so increase the width of the 55 outer end of the supporting ribs that the over-

hanging face or character bearing portion is properly supported regardless of where the slug is cut. Furthermore, since these fins or vanes extend from beneath the overhanging face or character bearing portion to the foot of the slug the footage necessary for the additional support is also provided.

For a more detailed description of the invention reference may be made to the accompanying drawing. In this drawing, however, the invention has been shown merely by way of example and in preferred form, and obviously many variations and modifications may be made therein which will still be comprised within its spirit. It is to be understood, therefore, that the invention is not limited to any specific form or embodiment, except insofar as such limitations are specified in the appended claims.

Referring to the drawing:

Fig. 1 is a front elevational view of a mold 20 embodying the features of the present invention;

Fig. 2 is a sectional view taken along the line 2—2 of Fig. 1;

Fig. 3 is a sectional view taken along the line 3—3 of Fig. 1; and

Fig. 4 is a perspective view of a slug cast in the improved mold.

As shown, the mold comprises a cap portion 10, a body portion 11 and end liners 12 and 13 which define a mold slot or cavity 14 in which a slug is cast. The mold shown being of the head-letter or display variety its cap portion 10 is provided with a series of tapered core members or sections 15. These sections terminate short of the body portion 11 to provide a longitudinal recess 16 in which a thin body portion 17 of the slug is cast and short of the front face of the mold to provide a longitudinal recess 18 in which an overhanging face or character bearing portion 19 of the slug is cast, and they are separated by fore-and-aft recesses 20 in which transverse ribs 21 are cast to support the overhanging face or character bearing portion 19. As is usual in molds of the sort shown, the core sections are so formed and spaced that when a slug is cast and thereafter cut to a standard length a transverse rib 21 will be beneath each end of the overhanging face or character bearing portion of the slug to provide the necessary support therefor.

As stated heretofore, however, it is desirable in 50 many instances to cut a slug cast in a mold of this sort at an odd length, and when this is done it frequently happens that one end of the overhanging face or character bearing portion 19 extends so far beyond a supporting rib 21 that 55

it fails for lack of support when subjected to pressure.

According to the present invention, however, such molds are improved to the extent that while a skeleton slug may be cast therein, yet the width of the outer end of the supporting ribs 21 is so increased that in the event the slug is cut to lengths other than standard lengths the overhanging face or character bearing portion 19 thereof will be properly supported, and to this end the upper end of the side faces of the core sections 15 are provided with fore-and-aft grooves 22 in which fins or vanes 23 are cast which extend outwardly along the sides of the supporting ribs 21 from beneath the overhanging face or character bearing portion 19 to the foot of the slug.

A slug cast in a mold so improved, therefore, comprises the usual thin body portion 17 and the usual overhanging face or character bearing portion 19. The width of the outer end of the transverse supporting ribs 21, however, which are cast in the recesses between the core sections is increased by the fins or vanes 23 which project outwardly along the sides of the ribs from beneath the overhanging face or character bearing portion 19 to the foot of the slug. The reinforcing fins or vanes 23 thus formed provide additional support along the edge of the overhanging face or character bearing portion 19 of the slug, regardless of where the slug is cast. Also, since the fins or vanes 23 extend fore-and-aft from beneath the overhanging face or character bearing portion 19 to the foot of the slug the footage necessary for the additional support is provided.

In the embodiment of the invention illustrated, in order to keep down the weight of the slug, the right-hand end core section is not grooved and the left-hand end core section is provided with a single groove, this being permissible since these sections are so narrow that in the event a slug is cast and then cut through the recess formed by either of these sections, as here shown, the overhanging face or character bearing portion of the slug will be properly supported.

Having thus described my invention, I claim:

- 50 1. In or for a slug casting machine, a mold comprising side and end walls defining between them a mold cavity, and a core section supported within said cavity, said core section having a groove along a side face.
- 55 2. In or for a slug casting machine, a mold comprising side and end walls defining between them a mold cavity, and a core section supported within said cavity and terminating short of the front face of the mold, said core section having a fore-and-aft groove along a side face.
- 60 3. In or for a slug casting machine, a mold comprising side and end walls defining between them a mold cavity, and a series of core sections supported within said cavity, certain of said core

sections having a groove along their side faces.

4. In or for a slug casting machine, a mold comprising side and end walls defining between them a mold slot or cavity, and a series of core sections supported within said cavity and separated by fore-and-aft recesses, certain of said core sections being provided with fore-and-aft grooves which open from said recesses.

5. In or for a slug casting machine, a mold comprising side and end walls defining between them a mold slot or cavity, and a series of core sections supported within said cavity and separated by fore-and-aft recesses, certain of said sections terminating short of the front face of the mold and provided with fore-and-aft grooves which open out of said recesses.

6. In or for a slug casting machine, a mold comprising a cap portion, a body portion and end liners defining between them a mold slot or cavity, and a series of core sections supported within said cavity by the cap portion, said core sections being separated by fore-and-aft recesses and terminating short of the front face of the mold to provide a longitudinal recess, and certain of said sections being provided with a fore-and-aft groove along the side face thereof.

7. In or for a slug casting machine, a mold comprising a cap portion, a body portion and end liners defining between them a mold slot or cavity, and a series of core sections supported within said cavity by the cap portion, said core sections being separated by fore-and-aft recesses and terminating short of the body portion to provide a longitudinal recess and short of the front face of the mold to provide a longitudinal recess, and certain of said core sections being provided with a fore-and-aft groove along the side face thereof.

8. A type bar or slug comprising a thin body portion, an overhanging face or character bearing portion, and a plurality of ribs for supporting said overhanging face or character bearing portion, certain of said ribs being widened at their outer ends to increase the supporting area beneath the overhanging face or character bearing portion.

9. A type bar or slug comprising a thin body portion, an overhanging face or character bearing portion, and a plurality of ribs for supporting said overhanging face or character bearing portion, certain of said ribs being provided at their outer ends with a fin or vane which extends outwardly therefrom to increase the supporting area beneath the overhanging face or character bearing portion.

10. A type bar or slug comprising a thin body portion, an overhanging face or character bearing portion, and a plurality of ribs for supporting said overhanging face or character bearing portion, certain of said ribs being provided with a fin or vane which extends outwardly therefrom from beneath the overhanging face or character bearing portion to the foot of the slug.

ANTHONY J. STOUGES.
